UNITED STATES PATENT OFFICE.

WILLIAM A. UNDERWOOD, OF WORCESTER, AND JOHN ZIMMERMAN, OF AUBURN,
MASSACHUSETTS.

CALENDER-ROLL GRINDER.

1,255,360.

Specification of Letters Patent. Patented Feb. 5, 1918.

Application filed March 23, 1917. Serial No. 157,038.

To all whom it may concern:

Be it known that we, WILLIAM A. UNDERWOOD and JOHN ZIMMERMAN, citizens of the United States, residing at Worcester and Auburn, respectively, in the county of Worcester and State of Massachusetts, have invented a new and useful Calender-Roll Grinder, of which the following is a specification.

10 This invention relates to a traverse grinding device, especially for use in the grinding of calender rolls without removing them from their bearings.

15 This invention is designed for the purpose of permitting use of a small grinding wheel, greatly increasing the speed, doing away with the chain arrangement heretofore used for traversing, providing a construction which will not be liable to get out of order, 20 providing a self-contained power unit, and a wheel truing device.

Other objects and advantages of the invention will appear hereinafter.

Reference is to be had to the accompanying drawings in which

Figure 1 is an end elevation of a calender with a preferred embodiment of this invention applied thereto;

30 Fig. 2 is a rear elevation of the grinding device removed from the calender and shown on a larger scale;

Fig. 3 is a plan of the same;

Fig. 4 is a side view;

35 Fig. 5 is a similar view illustrating the reversal of the wheel;

Fig. 6 is a rear elevation of a modified form;

Fig. 7 is a side view of the same, and

40 Fig. 8 is a sectional view on the line 8—8 of Fig. 6.

The invention is intended to be applied to a calender having frame ends A and calender rolls B to be ground. The frame is provided with series of bolt holes on its two opposite ends and two brackets 10 are bolted thereto so as to support the apparatus in the proper position for grinding a roll.

45 In the form of the invention shown in the first five figures there is a set of bolt holes for each calender roll and the device is set in a different place for grinding each of the rolls. On the brackets 10 is located a base 11 for supporting the frame 12 of the grinding device. An adjusting screw 13 is provided for

securing the frame in position and also for 55 adjusting it.

The frame 12 extends clear across the calender and is provided with longitudinal ways on which a slide 14 is adapted to move. This slide itself also is provided with transverse ways on which is slidably mounted a motor frame 15. This frame 15 is adjusted back and forth by a hand operated adjusting screw 16 as will be obvious. This frame has an arm at one end overhanging the parts 60 above described and adapted to extend inside the ends A of the calender toward the calender rolls B. It rests at the rear of the arm on planed surfaces on the slide and on its other side it supports an electric motor 65 17 centered over the supporting elements. This motor is provided with a pulley 18 adapted to drive a pulley 19 fixed to a shaft 20 journaled in bearings on the end of the arm. This shaft is shown as provided with 70 a roll grinding wheel 21, and it is also shown as extending beyond its bearings so that the grinding wheel can, if desired, be placed beyond either end as shown in dotted lines in Fig. 3. It will be obvious that the wheel can 75 be brought up to proper position to grind a calender roll by the mere adjustment of the screw 16.

On the end of the frame 12 is a shaft 23 provided with a cone pulley 24 and a gear 80 25. This gear is connected by suitable gearing with a traverse screw 26 and is designed to operate it, the cone pulley being driven from an external source of power preferably. This screw is connected with the frame 12 85 by a half nut 27 which is operated by a handle 28 to bring it into or out of engagement with the screw, at any given point along the traverse, whereby the rotation of the screw will feed the slide 14 along the frame. On 90 the end of the frame 12 is a pivoted arm 30 supporting certain of the gears and adjustable about the center of the screw 26 to bring either one of a pair of gears 31 into mesh with the gear 25 so as to control the direction 95 of rotation of the screw 26, as will be obvious. The half nut can be thrown out when the screw is to be reversed. This arm is adapted to be fixed in its two extreme positions by a spring-pressed pin 32 operated by 100 a handle 33.

On the arm 15 we have shown a wheel-truing device mounted on a bracket 35 car-

ried by the arm and having a transverse slide 36 carried in ways thereon and operated by a screw 37. On this slide is a screw 38, and a hand wheel for operating it. The screw carries a diamond point 39 adapted to be secured in position thereon by a small set screw 40. This can be adjusted up to the proper position and moved back and forth across the face of the wheel 21 by manipulating the screw 37 as will be obvious. In this way the wheel can be trued up conveniently and the truing device can, if desired, be kept in position on the frame or applied to it only when it is to be put into the same. Integral oil wells 41 are shown for the shaft 20 having end openings.

It will be seen that with this construction a small grinding wheel can be employed and adjusted up to the work in a very simple and convenient manner, and also that it can be driven at a high speed by the motor and that the traversing arrangement is independent of the wheel-truing connections and is hand controlled. By doing away with the old chain traversing device and substituting a screw the machine is made more durable and less likely to need repairs. The reduction in the size of the wheel is an important feature in this art because the ordinary large wheel cannot be supported in such a way as to run at a good cutting speed without chattering while the small wheel can be run up to 2100 this giving better cutting action and a greater speed of operation.

In the form shown in the last three figures, the device is mounted in the same way but the frame 12 is provided with end uprights 42 which support a driving shaft 43. This driving shaft is operated from an external source of power by a belt on a pulley 44, thus eliminating the motor shown in the other figures. The frame 12 is provided with the screw 26 shown in the other figures, and connected in the same way with a slide 45 traveling on ways on the frame 12.

This slide is provided with a pulley 46 which slides with it and is adapted to engage two intermittent keys 47 on opposite sides of the shaft 43 so that it will rotate with that shaft in all positions of the slide. Pivotally mounted on this slide concentric with the shaft 43 is a frame 48 having an inwardly extending arm 49 bolted thereto. The slide is provided with a rotary worm 50 operated by a handle 51 and meshing with a segmental worm gear 52 fixed on the frame 48. By turning this worm 50 therefore, the arm 49 can be raised and lowered about the center of the shaft 43 as a pivot.

The pulley 46 is adapted to transmit power by a belt to a pulley 53 on a shaft 54 carried by the arm 49 and carrying the grinding wheel 21. The arm 49 also supports a wheel-truing device 55 similar to the

one shown in the other figures, but located above the arm and somewhat simplified. This device operates in a manner substantially the same as the other except that the power for driving the wheel is derived through the shaft 43 from an external source and the arm 49 can be set at different angles so as to grind two calender rolls from one position of frame 12.

Although we have illustrated and described only two forms of the invention we are aware of the fact that other modifications can be made therein without departing from the scope of the invention as expressed in the claims. Therefore we do not wish to be limited to all the details of construction herein shown and described, but what we do claim is:—

1. In a portable calender roll grinder, the combination of a frame adapted to be applied directly to the end housings of a calender at different elevations, an arm carried by said frame and adapted to project in between the end housings of the calender frame, means on the frame for adjusting said arm so as to bring it into proper relation to the calender rolls, a shaft located at each end of said arm, a grinding wheel on one shaft and means for driving it on the other, a screw carried by said frame and connected with said arm, and means independent of said driving means for rotating said screw to move the arm back and forth.

2. In a portable calender roll grinder, the combination of a slide, means for moving said slide by power as a whole back and forth longitudinally, a motor frame carried by said slide having an arm extending inwardly, means for adjusting said motor frame transversely on the slide, a grinding wheel carried at the end of said arm, a motor mounted on said motor frame over said slide so as to be centrally supported thereby, and means movable as a whole with the motor frame for driving said grinding wheel from said motor.

3. In a portable calender roll grinder, the combination of a slide, means for moving said slide by power as a whole back and forth longitudinally, a frame carried by said slide and having an arm extending inwardly, means for adjusting said frame and arm transversely, a grinding wheel carried at the end of said arm, a motor mounted on the frame over said slide so as to be centrally supported thereby, means for driving said grinding wheel from said motor, a longitudinal screw supported by the frame, means independent of said motor for rotating said screw, and means on said frame for engaging the screw whereby the rotation of the screw will move the arm longitudinally.

4. In a calender roll grinder, the combination of a slide, means for moving said

slide by power as a whole back and forth longitudinally, a frame carried by said slide and having an arm extending inwardly, means for adjusting said frame and arm transversely on the slide, a grinding wheel carried at the end of said arm, a motor mounted on the frame over said slide so as to be centrally supported thereby, means for

driving said grinding wheel from said motor, and hand controlled change speed 10 gearing for moving the slide in either direction.

In testimony whereof we have hereunto affixed our signatures,

WILLIAM A. UNDERWOOD.
JOHN ZIMMERMAN.
